UNITED STATES PATENT OFFICE.

GEORGE J. PILGER, OF SCRANTON, PENNSYLVANIA.

AIR-BRAKE SYSTEM.

1,274,193.

Specification of Letters Patent. Patented July 30, 1918.

Application filed July 10, 1916. Serial No. 108,401.

To all whom it may concern:

- Be it known that I, GEORGE J. PILGER, a citizen of the United States, residing at Scranton, in the county of Lackawanna and State of Pennsylvania, have invented certain new and useful Improvements in Air-Brake Systems, of which the following is a specification, reference being had to the accompanying drawings.
- 10 This invention relates to certain improvements in air brake systems and has relation more particularly to an attachment especially designed and adapted for use in connection with a triple valve as embodied in the system; and an object of the invention is to provide novel and improved means whereby upon applying the brake, the auxiliary reservoir pressure is prevented from flowing into the brake pipe or train line.
- 20 The invention also has for an object to provide an attachment coacting with the triple valve in an air brake system whereby the brakes are prevented from creeping on while the train is in transit or upon the re-25 coil of air while releasing.

The invention consists in the details of construction and in the combination and arrangement of the several parts of my improved air brake system whereby certain 30 important advantages are attained and the device is rendered simpler, less expensive and otherwise more convenient and advantageous for use, all as will be hereinafter more fully set forth.

35 The novel features of the invention will hereinafter be definitely claimed.

In order that my invention may be the better understood, I will now proceed to describe the same with reference to the accompanying drawings, wherein—

Figure 1 is a diagrammatic view partly in elevation and partly in section illustrating an embodiment of my invention; and

Fig. 2 is a fragmentary sectional view 45 illustrating a further embodiment of my invention.

As disclosed in the accompanying drawings, V denotes a triple valve of the well known type K and which includes the main 50 piston 1 provided with the piston ring 2 and which co-acts with the feed port 16 formed in the side wall of the piston chamber P.

When the piston 1 is on service lap position the port 3 is partially closed. The port 3 is 55 in communication, through the medium of

the line 4, with the port 5 produced in the casing 6 and which is also in communication, through the medium of the line 7, with the auxiliary reservoir chamber of the triple valve.

60 The casing 6 affords a valve chamber C and the opposed walls of the chamber C are provided with the ports 8 in communication with the port 5 and affording the valve seats 9 and 9^a with which coacts the valve member 10.

65 The valve member 10 as disclosed in Fig. 1 is carried by the diaphragm 11 intersecting the chamber C whereby it will be perceived that the flow through the port 5 may be controlled. The diaphragm 11 is also provided with a restricted opening 12.

70 When the piston 1 is in full release the port 3 is opened which will allow the air at the head end of the train to force the diaphragm 11 toward the auxiliary side, the port or restricted opening 12 being insufficient to accommodate the air. The air on the train pipe side of the diaphragm will 75 force the valve 10 to close the seat 9^a and to maintain the same closed until sufficient air has passed through the restricted port 12 and the pressure in the chamber C on opposite sides of the diaphragm 11 is equalized, then the tension of the diaphragm 11 will 80 open the valve 10 and allow the air to flow into the auxiliary until the pressure on the 85 brake pipe side of the diaphragm 11 again causes the valve (b) to close and the diaphragm will continue to intermittently vibrate until there is a substantially permanent equalization of air upon the diaphragm 11. In applying the brake the piston 1 is 90 in full service position and the port 3 entirely closed resulting in the pressure from the auxiliary reservoir only acting upon the piston 1. When the piston 1 goes back to service lap as illustrated in Fig. 1, of the accompanying drawings the port 3 will be 95 partially opened. When the piston 1 is in service lap and there is a leaky slide valve or a leaky graduating valve (if not too great) this partial opening of the port 3 will 100 permit pressure to be delivered to the auxiliary and thereby prevent the brake from 105 releasing.

In the form of invention illustrated in Fig. 2 in lieu of a diaphragm I employ a piston within a valve chamber 6^a and which has the arms a' and b' encircled by the 110

equalizing springs 14 which serve to normally maintain the piston 15 in a neutral position.

From the foregoing description, it is thought to be obvious that an air brake system constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. In combination with the piston chamber and piston of a triple valve, a valve chamber in communication with the piston chamber at two points spaced longitudinally of the piston chamber, said piston partially closing the point of communication remote from the auxiliary side of the piston when the piston is on service lap position, a vibratory partition intersecting the valve chamber and provided with a restricted opening, and valve members carried by the partition for alternately opening and closing the points of communication between the valve chamber and piston chamber.

30
35

2. In combination with the piston chamber and piston of a triple valve, a valve chamber in communication with the piston chamber at two points spaced longitudinally of the piston chamber, said piston partially closing the point of communication remote from the auxiliary side of the piston when the piston is on service lap position, a vibratory partition intersecting the valve chamber and provided with a restricted opening, and valve members carried by the partition for alternately opening and closing the points of communication between the valve chamber and piston chamber.

40
45
50

2. In combination with the piston chamber and piston of a triple valve, a valve chamber in communication with the piston chamber at two points spaced longitudinally of the piston chamber, said piston partially closing the point of communication remote from the auxiliary side of the piston when the piston is on service lap position, a vibratory partition intersecting the valve chamber and provided with a restricted opening, and valve members carried by the partition for alternately opening and closing the points of communication between the valve chamber and piston chamber, said partition normally maintaining the valves in open position.

55
In testimony whereof I hereunto affix my signature in the presence of two witnesses.

GEORGE J. PILGER.
